UNITED STATES PATENT OFFICE.

JOHN HILL, OF WEST MERIDEN, CONNECTICUT, ASSIGNOR TO MERIDEN SILVER-PLATE COMPANY, OF SAME PLACE.

DESIGN FOR PICKLE-JARS OR CASTERS.

Specification forming part of Design No. 5,273, dated September 19, 1871.

To all whom it may concern:

Be it known that I, JOHN HILL, of West Meriden, in the county of New Haven and State of Connecticut, have invented a new and original Design for Pickle-Jars; and I do hereby declare the following, when taken in connection with the accompanying drawing and the letters of reference marked thereon, to be a full, clear, and exact description of the same, and which said drawing constitutes part of this specification and represents a side view.

This invention relates to a design for glass jars, such as are placed in metallic frames for table use, and commonly called "pickle-casters," hence the term "pickle-jars" applied to this invention; and the invention consists in the peculiar configuration of the jar, as shown in the accompanying illustration.

The form of the jar is four-sided or square, each side gradually increasing in width from the bottom toward the top. Near the top the neck is drawn in and fitted with a cover, C, of pyramidal form, all substantially as shown in the accompanying illustration, the cover being usually provided with a metal knob or ornament on the top. The surfaces may be ornamented to suit the taste of the maker or wants of the trade.

I claim as my invention—

The design for pickle-jars, as described and shown, with or without a cover.

JOHN HILL.
